UNITED STATES PATENT OFFICE

2,191,246

RAILWAY SWITCH PISTON AND CYLINDER DEVICE

Oscar W. Andersen, Flossmoor, Ill., assignor to
Pettibone Mulliken Corporation, Chicago, Ill.,
a corporation of Delaware

Application April 30, 1938, Serial No. 205,321

10 Claims. (Cl. 188—100)

My invention relates to railway switches of the automatic return type and involving piston and cylinder mechanism so constructed as to permit the switch points to be moved out of set position in the reverse travel of rolling stock through the switch and thereafter automatically return to set position; the cylinder of the mechanism containing non-freezing fluid, such as for example oil, which exerts a controlling effect, through the displacement thereof by the mechanism, on the movement of the switch points.

An example of the type of switch constructions to which my invention relates is that disclosed in U. S. Letters Patent No. 1,710,336 and 1,828,383, granted April 23, 1929, and October 20, 1931, respectively, employing double acting piston and cylinder mechanism effecting the return of the switch points to set position, either switch-open or switch-closed position, in the reverse travel of rolling stock through the switch; the mechanism referred to comprising a coil spring in the cylinder and so associated with parts of the mechanism that it effects return, under the retarding effect of a body of non-freezing liquid in the cylinder, of the switch points to either set position, whether in such set position the switch is open or closed, the piston and cylinder mechanism having a filler opening of such construction as to insure the provision of an air space above the liquid, as shown in said Patent No. 1,828,383.

It has been found in practice that the cylinders of switch mechanisms of the general type above referred to often contain moisture, particularly when of the more specific type shown in said Patent No. 1,828,383 and involving the air space referred to; the moisture in cold weather freezing and sometimes interfering with the proper operation of the piston and cylinder mechanism and consequently the parts with which it is connected. Also, sometimes cinders, or other foreign solid matter, enter the filler openings and find their way into the cylinders interfering with the proper operation of the mechanism.

One of my objects is to provide improvements in switch mechanism of the character above referred to, whereby freezing of moisture in the cylinders and danger from the entry of foreign solid matter into the cylinders will be avoided, thus avoiding interference with the proper operation of the mechanism and affording greater safety of railway operation.

A further object is to provide cylinder structures of such construction that the cored portions thereof provided as castings, may be readily

cleaned preparatory to the initial assembly of the parts of the cylinder structures.

Other objects will be apparent from the following description:

I have chosen to illustrate my invention, but without intending to limit it thereto, in connection with switch mechanism of the character shown in said Letters Patent No. 1,710,336 and 1,828,383, a description of the accompanying drawings, being as follows:

Figure 1 is a view in longitudinal sectional elevation of the piston and cylinder mechanism of the railway switch construction, the section being taken at the irregular line 1—1 on Fig. 2 and viewed in the direction of the arrow.

Figure 2 is a cross section of the piston and cylinder mechanism, the section being taken at the line 2 on Fig. 1 and viewed in the direction of the arrow.

Figure 3 is a view like Fig. 1 of a modification of the construction shown in Figs. 1 and 2.

Figure 4 is a section taken at the line 4—4 on Fig. 3 and viewed in the direction of the arrows; and

Figure 5, a view like Fig. 1 of a railway switch construction of the single acting type and embodying my invention.

Referring to the construction shown in Figs. 1 and 2; the piston and cylinder mechanism shown is provided as a link located between the switch-stand for throwing the switch into either set position, and linkage connected with the switchpoints of the switch, as in the case of the piston and cylinder mechanism shown in said Patent No. 1,710,336.

The piston and cylinder mechanism comprises a cylinder 3 formed of a cylinder shell 4 and cylinder ends 5 and 6, the cylinder end 5 being shown as provided with apertured spaced apart ears 7 for connection with the linkage (not shown) to which the switch points (not shown) would be connected as in the case of the patent last referred to.

The cylinder 3 contains a coil spring 8 bearing at its opposite ends against pistons 9 and 10 located in the cylinder and slidably mounted on a rod 11 slidable in the cylinder end 6, the rod 11 being provided for connection with the switch-throw mechanism, as in the case of the similar rod in the patent last referred to.

The rod 11 is provided with abutments 12 and 13 opposing shoulders 14 and 15, respectively, on the pistons 9 and 10. The pistons 9 and 10 are apertured as indicated at 16 and 17 at which portions they cooperate with spring-backed valve

rings 18 and 19, respectively, which function as in the case of the valves of said patents.

Surrounding the cylinder shell 4 and spaced therefrom is a hollow open-ended member 20 which is positioned between the end members 5 and 6. Bolts 21 extending through openings in the end members 5 and 6 screw into the ends of the member 20 to connect these parts together and by the abutment of the end members 5 and 10 6 against the ends of the cylinder shell 4 secures this shell in place.

The space thus afforded between the shell 4 and the member 20 and represented at 22, surrounds the shell 4 and forms a closed settling 15 chamber having a filler opening 23 in its top shown as equipped with a cylindrical screen member 24 and adapted to be closed by a plug 25 screwed into this opening; the annular surrounding wall of the opening 23 being shown as depending to an elevation below the top inner surface of the member 20, as represented at 26 and forming a skirt or sleeve which insures provision of the air space referred to in the charging of the mechanism with non-freezing liquid.

25 The cylinder 3 opens into the chamber 22 through apertures in the top and bottom portions of the shell 4. Two of such apertures are shown at both of these locations as represented at 27 and 28, the apertures 27, shown as round openings, being preferably relatively small.

To prepare the mechanism for use, a suitable non-freezing liquid, as for example oil, is charged into it through the filler opening 23, the liquid entirely filling the cylinder 3 and filling the 35 chamber 22 to a height substantially coincident with the underside of the depending wall 26 of the filler opening and thus below the extreme upper portion of the inner surface of the member 20, thus providing a space above the liquid in the chamber 22 in which the liquid may rise and fall responsive to the relative movements of the piston and cylinder mechanism and the rod 11. As will be understood, the provision of the skirt or sleeve 26, insures against the complete filling of the chamber 22 and the elimination of the desired 40 expansion space for the liquid.

Particularly as a body of air is confined within the mechanism above the liquid level in the chamber 22 and as the air will contain at least 50 some moisture, lowering of the temperature of the air will result in condensation of the moisture and its gravitation through the non-freezing liquid. Such of the condensed moisture as does not gravitate through the chamber 22 and around the shell 4 to the bottom of the chamber 22, will pass 55 through the openings 27 into the cylinder 3 and will drain from the latter through the openings 28 into the chamber 22. Thus such moisture within the mechanism as may become condensed will not, if any portion of it gains access to the cylinder 3, be retained therein but will flow into the bottom of the chamber 22 wherein, if the 60 temperature of the atmosphere is sufficiently low, it will freeze, but in which chamber it can do no harm as none of the operating parts are contained therein.

The cylinder 3 is thus maintained free of congealed moisture and thus interference with the proper operation of the operating parts of the structure by congealed moisture, is prevented.

70 The structure also serves to minimize danger of interference with the proper operation of the parts and damage thereto, by the entrance of solid foreign matter, as for example cinders into the chamber 22. Such of the solid matter as does

not gravitate to the bottom of this chamber by passing around the side of the shell 4, but enters the cylinder through either of the openings 27, will gravitate through the lower apertured portion of the cylinder 3 into the bottom of the chamber 22.

To make for economy of structure without impairing the proper operation of the device, the hollow member 20 is preferably of substantially the cross-sectional shape shown in Fig. 2, namely, vertically elongated to cause the chamber 22 at both its top and bottom to be relatively deep, compared with its sides, the top portion thereof being somewhat deeper than the bottom portion.

The feature of forming the piston chamber 3 15 and the chamber 22 of separable parts comprising the shell 4, member 20, and end members 5 and 6, is of advantage as it permits of the ready thorough cleaning of the cored portions of such structures provided as castings, preparatory to the 20 initial assembly of the parts of the cylinder structures, the relatively large lengthwise extending openings therethrough permitting of ready access to the surfaces to be cleaned by suitable cleaning tools.

25 Referring to Figs. 3 and 4 of the drawings, the construction shown therein is substantially the same as that illustrated in Figs. 1 and 2 except that instead of providing the settling means as a continuous chamber surrounding the cylinder 30 containing the operating parts as in Figs. 1 and 2, this chamber, represented at 29, is formed only part way around the cylinder at the lower side thereof, and the liquid receiving space at the upper side of the cylinder is provided as a chamber 30 separate from the chamber 29. These 35 separate chambers may be provided in any desirable way. As shown they are formed by providing lower and upper castings 31 and 32, respectively, secured to the cylinder herein represented at 33 40 and shown as a casting, by screw bolts 34 extending through flanges 35 at the ends of the cylinder 33 and into the ends of the castings 31 and 32 and also by screw bolts 36 passing through opposite edges of the castings 31 and 32 and into 45 bosses formed on the cylinder 33.

In Fig. 5 I have shown an embodiment of the invention as applied to a piston and cylinder mechanism of the single acting type and involving one piston only, such as for example a mechanism of the general construction shown in my United States Letters Patent No. 1,710,335 granted April 23, 1929. As the particular internal operating parts of the mechanism of this construction form no part of my present invention 55 description thereof appears to be unnecessary.

In this construction the cylindrical shell in which the operating parts are located is represented at 37 and the end members between which the cylinder shell 37 is clamped, at 38 and 39, the cylinder shell 37 having openings 40 and 41 in its top and bottom, respectively. Surrounding the cylinder shell 37 and spaced therefrom throughout its extent, as in the case of the construction in Figs. 1 and 2, is a hollow open ended member 65 42 positioned between the end members 38 and 39 and held in place thereby as in the case of the construction of Figs. 1 and 2. The member 42 may be of the same form as the member 20 of Figs. 1 and 2 and similarly provided with a 70 plug-equipped filler opening 23 at its top surrounded by a depending continuous flange 26 serving the function of the similar flange of Figs. 1 and 2.

75 As will be understood, the construction as

shown serves as described above in the case of the construction shown in Figs. 1 and 2, to insure the provision of a space above the oil in the chamber represented at 43 and formed by the cylinder shell 37 and member 42, in which the liquid may rise and fall responsive to the relative movements of the operating mechanism in the cylinder shell 37, and also a lower space into which moisture and solid matter entering the structure will gravitate, maintaining the cylinder shell 37 free from such objectionable substances.

While I have illustrated and described certain particular constructions embodying my invention and illustrated and described it as applied to certain particular types of switches, I do not wish to be understood as intending to limit it thereto as the same may be variously modified and altered, and the invention embodied in other forms of structure and in other types of railway switches without departing from the spirit of the invention.

What I claim as new, and desire to secure by Letters Patent, is:

1. In a piston and cylinder device of a railway switch, the combination with its cylinder for liquid and the operating parts therein, of a settling chamber having a filler opening, said chamber opening into said cylinder at the upper portion of the cylinder and through the bottom of the cylinder.

2. In a piston and cylinder device of a railway switch, the combination with its cylinder for liquid and the operating parts therein, of a settling chamber having a filler opening, said chamber opening into said cylinder through the top and bottom of said cylinder.

3. In a piston and cylinder device of a railway switch, the combination with its cylinder for liquid and the operating parts therein, of a settling chamber having a filler opening, the surrounding wall of said filler opening extending below the top of said chamber, said chamber opening into said cylinder at the upper portion of the cylinder and through the bottom of the cylinder, the lower edge of said surrounding wall extending at least at as high an elevation as the upper extremity of the inner surface of said cylinder.

4. In a piston and cylinder device of a railway switch, the combination with its cylinder for liquid and the operating parts therein, of a settling chamber having a filler opening the surrounding wall of which extends below the top

of said chamber, said chamber opening into said cylinder at the upper portion of the cylinder and through the bottom of the cylinder, the lower edge of said surrounding wall extending above the upper extremity of the inner surface of said cylinder.

5. In a piston and cylinder device of a railway switch, the combination with its cylinder for liquid and the operating parts therein, of a settling chamber surrounding said cylinder, said chamber having a filler opening and said cylinder having openings at its upper portion and in its bottom communicating with said chamber.

6. In a piston and cylinder device of a railway switch, the combination with its cylinder for liquid and the operating parts therein, of a settling chamber surrounding said cylinder, said chamber having a filler opening in its upper portion, the surrounding wall of said filler opening extending below the top of said chamber, said cylinder having openings in its top and bottom communicating with said chamber.

7. In a piston and cylinder device of a railway switch, the combination with its cylinder for liquid and the operating parts therein, of a settling chamber in communication with the upper portion of said cylinder and extending down along a side of the cylinder.

8. In a piston and cylinder device of a railway switch, the combination with its cylinder for liquid and the operating parts therein, of a settling chamber in communication with the upper portion of said cylinder and extending down along the side of the cylinder at opposite sides of the center line of the cylinder.

9. In a piston and cylinder device of a railway switch, the combination with its cylinder for liquid and the operating parts therein, of a settling chamber in communication with the upper portion of said cylinder and extending down along a side of the cylinder, said chamber having a filled opening the surrounding wall of which extends below the top of said chamber.

10. In a piston and cylinder device of a railway switch, the combination with its substantially horizontal cylinder for liquid and the operating parts therein, of a substantially horizontal settling chamber surrounding said cylinder, said chamber having a filler opening and said cylinder having openings at its upper portion and in its bottom communicating with said chamber.

OSCAR W. ANDERSEN.
